Attis

UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

CONDUCTOR-GRIP.

1,206,085.

Specification of Letters Patent. Patented Nov. 28, 1916.

Original application filed November 18, 1910, Serial No. 592,989. Divided and this application filed April 19, 1912. Serial No. 691,987.

To all whom it may concern:

Be it known that I, REUBEN B. BENJAMIN, a citizen of the United States, residing at Chicago, in the county of Cook and State 5 of Illinois, have invented new and useful Improvements in Conductor-Grips, of which the following is a full, clear, concise, and exact description, reference being had to the accompanying drawing, forming a part of 10 this specification.

My invention pertains to conductor grips, and particularly to conductor grips as employed in connection with pendant electrical devices, such for instance as pendant 15 switches or sockets.

It is the object of my invention to provide a conductor grip which will perform its function efficiently and reliably, and which will be of a simple and economical construction.

I have described in the following specification, and shown in the accompanying drawings, a conductor grip as applied to a pendant switch of the kind described in my 25 pending application Serial No. 592,989, filed November 18th, 1910, of which this application is a division. It is to be understood, however, that my invention may be employed in connection with electrical devices other than pendant switches, and that 30 changes may be made in the construction of the conductor grip which I have described and shown, without exceeding the scope of my invention as defined in the appended 35 claims.

In the drawings: Figure 1 is a side elevation of a pendant switch provided with a conductor grip constructed in accordance with my invention; Fig. 2 is an elevation of 40 the same, partly in section, upon an enlarged scale, the section being taken on the line 2-2 of Fig. 1; Fig. 3 is a partially sectional view of the upper portion of the same, the section being taken on the line 3-3 of Fig. 2; and 45 Fig. 4 is a sectional plan, the section being taken on the line 4-4 of Fig. 2.

In the construction shown in the drawings, 12 designates the upper, and 13 the lower, portion of a two-part cylindrical casing, the parts of which are adapted to be secured together by means of threaded portions 14 and 15, respectively, with which they are formed. This casing contains an insulating base 16, of cylindrical form, the

lower end of which carries the switch mechanism, which latter is of the kind described in my pending application referred to above, and does not, therefore, require description here. The base 16 is securely held between the upper and lower portions of the casing, 55 when these portions are secured together, and is prevented from rotation with respect to the casing, by means of an inwardly extending projection 13^a, with which the casing portion 13 is provided, which projection 60 enters a corresponding recess 16^a formed in the lower part of the base 16. The upper end of the base 16 is formed with a pair of recesses 17 and 18 respectively through 65 which the conductors by which the switch is suspended are led to binding terminals 19 and 20 which are connected with the contacts which are to be bridged by the switch. The recesses 17 and 18 are disposed so as to 70 form between them a neck 21, the edges of 75 which form shoulders which are adapted to bind against the conductors entering the recesses 17 and 18, as will now be described.

An insulating disk 22 is placed in the part 12 of the casing, above the upper end 80 of the base 16, and is prevented from falling out of the casing, when the parts thereof are separated, by an inwardly extending bead 23 with which the casing part 12 is formed. The disk 22 is provided with a central aperture 24, through which the conductors may 85 pass, in entering the recesses 17 and 18. The casing part 12 is formed at its upper end with an open ended conical head 25 containing a pair of insulating gripping members 26. The gripping members 26 are made 90 so as to form, between the upper ends thereof, an elliptical opening having gripping edges 27, between which the conductors, shown in dotted lines in Fig. 3 and designated as 28 and 29 respectively, are securely 95 grasped when the gripping members 26 are forced up into the head 25 by the pressure exerted by the base 16 when the casing parts 12 and 13 are screwed together. Coil springs 100 12 and 13 are inserted between the gripping members 26 and tend to force them apart, so that, when the parts 12 and 13 of the casing are separated and the insulating base 16 is removed, and the insulating disk 22 falls upon 105 the bead 23, the gripping members 26 may be separated, by the springs 30, to provide sufficient room between them for the inser-

tion or withdrawal of the conductors 28 and 29.

Supposing that the casing parts 12 and 13 have been separated and the insulating base 16 withdrawn; that the insulating disk 22 is resting upon the bead 23; and that the gripping members 26 have been separated by the springs 30 and are resting upon the disk 22; it will be seen that the conductors 28 and 29 may be inserted easily through the wide space between the gripping members 26 and through the opening 24 of the disk 22, into the recesses 17 and 18 of the base 16. When this has been done, the base 16 may be replaced in the casing, the slack of the conductors 28 and 29 being pulled out through the members 26. Upon the parts 12 and 13 being screwed together, the upper end of the insulating base will press upon the disk 22, and thereby upon the gripping members 26, and will force these members up into the head 25 of the casing part 12. The result of this will be that, owing to the wedge action of the gripping members 26 in the conical head 25, these members will be forced together and the conductors 28 and 29 will therefore be securely gripped between the gripping edges 27 of these members. At the same time the conductors 28 and 29 are separately gripped between the edges of the neck 21, between the recesses 17 and 18, and the edge of the aperture 24 in the disk 22, the aperture 24 being made of a convenient size for this purpose. The conductors are therefore gripped at two points, the double cord made up of the conductors 28 and 29 being gripped between the edges 27 of the members 26, and the separate conductors being gripped between the edges of the neck 21 and the edge of the aperture 24 in the disk 22. By this means a very secure holding of the conductors is obtained, since, even if the grip effected by the edges 27 of the members 26, should fail, the conductors will still be secured between the edges of the neck 21 and the edge of the aperture 24 in the disk 22. The danger of strain being imparted to the binding terminals is thus entirely precluded.

Having thus described my invention, what I claim as new and desire to secure by Letters Patent, is:

1. An electrical fixture comprising a binding terminal for a conductor, a conductor grip comprising a plurality of members adapted to grasp the conductor between them when said members are forced together, releasable means for forcing said members together, and means for separating said members when said last-named means is released.
2. An electrical fixture comprising a binding terminal for a conductor, a conductor grip comprising a pair of oppositely disposed members adapted to grasp the conductor between them when said members

are forced together, releasable means for forcing said members together, and springs disposed between said members for separating the same when said last-named means is released.

3. In an electrical device, an insulating member, casing means therefor including two separably connected parts, a pair of conductor gripping members mounted in one of said parts and means for retaining said gripping members in said part, said means comprising an insulating disk permanently secured in said part and having a longitudinal movement therein.

4. In an electrical device, the combination with casing means comprising a pair of endwise separable portions, of a conductor-carrying member disposed in said casing, a plurality of conductor-gripping members mounted in one of said casing portions, means for forcing said gripping members together in gripping engagement with a cord when one of said casing portions is moved toward the other, and means for securing said gripping members in position when the casing portions are separated.

5. In an electrical device, the combination with casing means comprising a pair of endwise separable portions, of a conductor-carrying member disposed in said casing, a plurality of conductor-gripping members mounted in one of said casing portions, means for forcing said conductor-gripping members together in gripping engagement with a cord when one of said casing portions is moved toward the other, and means for securing said conductor gripping members in position when said casing portions are separated.

6. In a cord grip, the combination with a cone-shaped casing, of a plurality of wedge-shaped gripping members fitting therein between which a conductor cord is gripped, and means for forcing said members in said casing to cause them to move together to grip the cord, and means tending to normally separate said gripping members.

7. In a cord grip, the combination with a cone-shaped casing, of a plurality of wedge-shaped gripping members fitting therein, between which a conductor cord is gripped, means for forcing said members in said casing to cause them to move together laterally to grip the cord, a member having an opening therein through which the cord is adapted to pass, a member having a projection adapted to be forced between and spread said conductors and to force them against the edges of said opening to individually grip the conductors of the cord.

8. In a cord grip for gripping a plurality of conductors, the combination with a casing, of a plurality of wedge-shaped gripping members, means whereby said members are

forced together by wedging engagement with said casing to grip the conductors collectively, a member having a center opening, an insulating base having a projection for interposition between the conductors and for forcing them individually into gripping engagement with the walls of said center opening.

9. In a device of the character described, 10 the combination with a casing having a conical extension at its top, of a plurality of wedge-shaped gripping members for gripping a plurality of conductors arranged in said extension and adapted to 15 be moved laterally together into gripping engagement with said conductors collectively by being forced into said casing,

an insulating disk having a central opening and arranged beneath said gripping members, an insulating conductor-carrying base 20 having a projection thereon insertible between the individual conductors and for forcing said conductors into gripping engagement with the walls of said central opening, and means for forcing the base into the 25 top of the casing to cause the cord and conductor-gripping members to operate.

In witness whereof, I have hereunto subscribed my name in the presence of two witnesses.

REUBEN B. BENJAMIN.
